UNITED STATES PATENT OFFICE.

HERBERT CHORLTON, OF HUNTINGTON, NEW YORK.

INTERNAL-COMBUSTION ENGINE OF THE SLEEVE-VALVE TYPE.

1,288,509.

Specification of Letters Patent. Patented Dec. 24, 1918.

Application filed August 14, 1915. Serial No. 45,483.

To all whom it may concern:

Be it known that I, HERBERT CHORLTON, a citizen of the United States, residing at Huntington, in the county of Suffolk and State of New York, have invented certain new and useful Improvements in Internal-Combustion Engines of the Sleeve-Valve Type; and I hereby declare that the following is a full, clear, and exact description 10 of the same.

My present invention relates to internal combustion engines of the sleeve valve type. The principal objects of my invention are to produce an internal combustion motor of the sleeve valve type in which the piston and the sleeve valves may be properly cooled and lubricated, and in which the formation of carbon in the combustion chamber, due to excess of lubricating oil in said chamber, 15 will be practically eliminated. These and the other objects of my invention will be more fully explained and pointed out in the following specification and accompanying drawings, in which Figure 1 is a vertical 20 sectional view of an engine cylinder and crank case, disclosing my invention, Fig. 2 is a plan view partly in section, and Fig. 3 is a vertical sectional view of a modification 25 of my invention.

Similar numerals refer to similar parts throughout the several views.

In the drawings the crank case 1 is provided with a removable bottom portion 2, secured in place by studs 3. The crank 35 shaft 4 is mounted in bearings 5 of the usual type. 6 is the connecting rod, 7 the piston, which is mounted to reciprocate in the cylinder 8, which is provided with a water-jacket 9. 9^a is the intake pipe connection and 9^b the discharge pipe connection.

The cylinder 8 is concentrically mounted in a cylindrical housing 10, which is secured to the crank case by studs 11, the cylinder 40 being secured in the casing 10 by studs 12. Between the outer walls of the cylinder and the casing 10 is a concentric cylindrical 45 chamber 13, in which are mounted the sleeve valves 14 and 15.

The walls of the cylinder are provided 50 with intake ports 16 and outlet ports 17, and the casing with intake port 18 and outlet port 19, and the sleeve 14 with intake ports 20 and outlet ports 21, and the sleeve 15 with intake ports 22 and outlet ports 23. 55 The crank shaft 24 is mounted in a separate chamber 25 and is operated by the

gears 26 and 27, and the chain 28. A connecting rod 29 causes the sleeve 14 to reciprocate in the chamber 13, and a connecting rod 30 causes the sleeve 15 to also reciprocate in said chamber, thereby causing the ports 20 and 22 to register with the ports 16 and 18 on the intake stroke of the piston, and the ports 21 and 23 to register with the ports 17 and 19 on the exhaust 60 stroke of the piston. The sleeves 14 and 15 also act as a pump and on the downward movement create a partial vacuum in the upper part of the chamber 13, which causes oil to be drawn from the lower part of the 70 chamber 25, through the pipe 31, into the upper part of the chamber 13. On the upward stroke the oil in the chamber 13 is forced down between the walls of the cylinder, the sleeves and the casing, and any 75 excess is returned to the chamber 25 through the pipe 32. The pipe 31 is provided with the ball check valve 33, which permits oil to flow from the chamber 25 to the chamber 13, but prevents the flow of oil from the 80 chamber 13 through the pipe 31 into the chamber 25. Pipe 32 is provided with a ball check valve 34 which is normally closed, but permits the flow of oil from the chamber 13 to the chamber 25.

The construction shown in Fig. 3 is substantially the same as that shown in Fig. 1, except that the cylinder in which the piston operates is not provided with a water-jacket, the water-jacket 35, as shown in said 90 Fig. 3, being in the outer casing instead of in the cylinder as shown in Fig. 1.

Heretofore it has been found difficult to properly lubricate the piston and sleeve valves in this type of motor, without supplying such a quantity of oil as to cause the oil to work its way into the combustion chamber and cause carbon in excessive quantities to form on the piston head and on the walls of the piston chamber. It is very desirable that the reciprocating sleeve valves should be made as light as possible, particularly in a high-speed motor, which is recognized as the most desirable type. In the types of these motors which were previously 100 constructed, where the sleeves were mounted around the piston and within the walls of the cylinder, the sleeves were compelled to take the side thrust of the piston and, therefore, were of necessity constructed with 105 walls so thin as to be unable to permanently withstand this very considerable strain 110

without being deformed from a cylindrical shape, or were of undue thickness and weight. In this construction they were also subjected to undue friction of the piston. It was also found difficult in the prior construction to properly cool the piston or the inner sleeve.

All of these difficulties have been obviated by my invention. The lower ends of the sleeves 14 and 15 are lubricated by the splash of oil from the crank case 25, and the upper ends of the sleeves by oil passing into the chamber 13 through the pipe 31, or from any other source. The piston is cooled by contact with the wall of the cylinder which is itself cooled by the water in the jacket 9, and the sleeves, except at the inlet and outlet ports, do not come into contact with the burning gases and they likewise are cooled, 13 by contact with the outer wall of the cylinder 8, and 14 by contact with the wall of the housing 10, which housing may be water-jacketed as shown in Fig. 3. By removing the pipe connection 9^a, and the studs 12, 25 the cylinder 8 may be withdrawn from the housing 10.

Having described my invention, what I claim as new is:

1. An internal combustion engine comprising a crank case, a cylindrical housing, a cylinder concentrically mounted in said housing, a piston adapted to reciprocate in said cylinder, a concentric chamber between the cylinder and the housing, reciprocating sleeve valves mounted in said concentric chamber, an auxiliary crank chamber closed against communication with the crank case, a crank shaft, connecting rods for operating said sleeve valves mounted in said auxiliary crank chamber, and a pipe in open communication with the lower part of the auxiliary crank chamber and said concentric chamber above said sleeve valves.

2. An internal combustion engine comprising a crank case, a cylindrical housing, a cylinder concentrically mounted in said housing, a piston adapted to reciprocate in said cylinder, a concentric chamber between

the cylinder and the housing, reciprocating sleeve valves mounted in said concentric chamber, an auxiliary crank chamber closed against communication with the crank case, a crank shaft, connecting rods for operating said sleeve valves mounted in said auxiliary crank chamber, and means for conveying oil from the auxiliary crank chamber to said concentric chamber above said sleeve valves.

3. An internal combustion engine comprising a crank case, a cylindrical housing, a cylinder concentrically mounted in said housing, a piston adapted to reciprocate in said cylinder, a concentric chamber between the cylinder and the housing, reciprocating sleeve valves mounted in said concentric chamber, an auxiliary crank chamber, a crank shaft, connecting rods for operating said sleeve valves mounted in said auxiliary crank chamber, and means for conveying oil from the auxiliary crank chamber to said concentric chamber and returning the surplus oil so conveyed to said auxiliary crank chamber.

4. An internal combustion engine comprising a crank case, a cylindrical housing, a cylinder concentrically mounted in said housing, a piston adapted to reciprocate in said cylinder, a concentric chamber between the cylinder and the housing, reciprocating sleeve valves mounted in said concentric chamber, an auxiliary crank chamber closed against communication with the crank case, a crank shaft, connecting rods for operating said sleeve valves mounted in said auxiliary crank chamber, and means actuated by the compression in the auxiliary crank chamber for conveying oil from the auxiliary crank chamber to said concentric chamber above said sleeve valves.

Signed at Huntington, in the county of Suffolk, and State of New York, this 26th day of July, 1915.

HERBERT CHORLTON.
